DESIGN FOR DRESS

Mary Mullen, Philadelphia, Pa., assignor to Roseau Bros. Inc., Philadelphia, Pa., a corporation of Pennsylvania

Application November 30, 1935, Serial No. 59,841

Term of patent 3½ years

To all whom it may concern:

Be it known that I, Mary Mullen, a citizen of the United States, residing at Philadelphia, in the county of Philadelphia and State of Pennsylvania, have invented a new, original, and ornamental Design for a Dress, of which the following is a specification, reference being had to the accompanying drawing, forming part thereof.

Figure 1 is a front elevational perspective view of the dress embodying the design.

Figure 2 is a rear elevational perspective view of the dress embodying the design.

The characteristic features of the design comprise the combination of a relatively full, short

skirt having a gathered waist line and having separated groups of relatively narrow stripes of different length rising from the lower edge of the skirt and terminating at points below the waist, a relatively less full bodice having short, puffed sleeves and a vertical row of buttons along its front center line, and a relatively wide, flat collar open at the front, as shown.

I claim:

The ornamental design for dress as shown and described.

In testimony whereof I have hereunto set my hand.

MARY MULLEN.
